UNITED STATES PATENT OFFICE.

GEORGE H. FRASER, OF BROOKLYN, NEW YORK.

MACHINE FOR CRUSHING OR GRINDING.

1,222,385.

Specification of Letters Patent.

Patented Apr. 10, 1917.

Original application filed March 16, 1905, Serial No. 250,474. Renewed July 3, 1916, Serial No. 107,467. Divided and this application filed June 29, 1915. Serial No. 36,966.

To all whom it may concern:

Be it known that I, GEORGE H. FRASER, a citizen of the United States of America, residing in the borough of Brooklyn, county 5 of Kings, city and State of New York, have invented certain new and useful Improvements in Machines for Crushing or Grinding, of which the following is a specification, being a division of my application filed 10 March 16, 1905, Serial No. 250,474.

This invention relates to machinery for crushing, grinding or pulverizing materials, and aims to provide certain improvements therein.

15 The invention relates more particularly to rock crushers of the type having a plurality of crushing rolls within an annular die in which the crushing is effected between the periphery of the rolls and the inner face 20 of the die. One example of this type of crusher is shown in the patent of H. L. Kent, granted May 7, 1901, No. 673,856, in which the die revolves and is held in position by the rolls, which latter are carried 25 by shafts held in bearings at the outside of the casing, the bearings being carried by slideways and pressed outwardly by springs, so that the rolls may slide in and out radially of the ring. The top roll in this 30 patent is shown as supporting the ring yielding, and the sliding frames carrying the shafts are of sectional construction, and both guide the shafts and transmit the crushing pressure from the springs to them.

35 My present invention aims to provide an improved crusher or pulverizer especially applicable to this general type.

To this end in carrying out my present invention in its preferred form, I provide 40 an improved arrangement of die and rolls, improved means for carrying the roll shafts, improved means for guiding such shafts, means for transmitting all or part of the crushing thrust from one roll to another so 45 as to relieve the bearing pressure or the spring pressure in whole or in part, and various details of improvement in the construction and arrangement of the various 50 parts of the crusher, all of which will be hereinafter more fully set forth with reference to the accompanying drawing which 55 is a fragmentary side elevation of a pulverizer embodying the preferred form of my invention, the view being partly broken away to show the yokes in mid-section.

Referring to the drawing, A is the casing, B is the ring or die, C, C¹ and C² are the crushing rolls, D, D¹ and D² are their shafts, E, E¹ and E² are their bearings, S, S¹ and S² are the crushing springs, and d, d¹ and d² 60 are adjusting screws.

The casing incloses the ring and rolls and supports them. The top roll in the construction shown carries the ring by acting against its inner face, and the other rolls 65 press outwardly against the inner face to crush the rock between their peripheries and such face. Their pressure may be adjusted by the springs and adjusting screws. The ring and rolls are driven in any suitable 70 manner, as by driving the shaft D for example. The feed delivers the rock on to the inner face of the ring, and the crushed rock flows off the sides of the ring and falls out through an opening f^o in the bottom 75 of the casing. The casing is made sectional to permit opening, as by being constructed as a base or bottom shell a and a cover or top shell b.

I will now describe in detail the preferred 80 form of my improvements as illustrated in the drawing.

According to one feature of improvement, I guide the bearings for the several shafts by a swinging guide or pivotal connection, 85 so that each can oscillate relatively to a predetermined axis if its movement radially of the ring is necessary. I prefer to so guide each shaft bearing, and to carry all from sections of the casing, which for this purpose I provide with transverse bearings c c¹, in which are mounted shafts g g¹, the shaft g being connected to the bearing E by links G on opposite sides of the casing, and by links G² to the bearing E², so that 95 each of these bearings is supported pivotally from its center, and the shaft g¹ being connected by similar links G¹ to the bearings E¹. This connection permits the bearings to rock toward and from the center of the 100 ring, but supports them against thrusts in the direction of drive of the ring, as well as in case of the lower bearings carrying part of their weight. The links are connected to the respective bearings by pins e 105 traversing the ends of the links and holes in projections f on the bearings. The links may be loosely connected to the shafts g g¹, but I prefer to connect only the links G loosely, so that they can rock independently 110

of each other, and to key or otherwise rigidly connect the links G^1 and G^2 to their shafts g^1 and g respectively, so that these links and their shafts make a rigid frame extending around the casing, and insuring parallel movement of the bearings at opposite sides of the latter. This construction attains a more advantageous guidance of the roll shafts than heretofore, and provides a much simpler and more economical means for correctly guiding them.

According to another feature of improvement, I provide a rigid bearing frame preferably consisting of a single U-shaped casting or yoke i straddling the casing and receiving the ends of the shaft at opposite sides thereof, so that these ends are assured of parallel bearings, and the number of parts necessary is reduced to the minimum. The bearing end j of each yoke is planed and covered by a bearing cap k , and the projections f for the supporting links are preferably cast integral with the end of the yoke so as to support the bearings from the yoke instead of from the cap, although I may support it otherwise. Each yoke is a relatively heavy casting in order to give not only the strength necessary to rigidity, but the weight desirable to the necessary crushing pressure or inertia. Each yoke is preferably formed with a spring pocket l for receiving the pressure spring, and has a screw-threaded aperture m for the corresponding adjusting screw. The spring pocket is formed in a central enlargement n on the outer side of the yoke, which is connected by a rib o and side flanges p with the bearing end j . The side flanges or legs of the yoke preferably converge toward the center as seen in the drawing.

According to another feature of improvement I preferably mount the top shaft so it can be adjusted vertically and so it can move upwardly in case of abnormal stress.

To retain the top yoke against falling sidewise, I prefer to provide a guide carried yieldingly by the casing, as the upwardly projecting guide s . These guides loosely receive the yoke near its center and limit its motion in forward or rearward direction. For adjusting it vertically, I prefer to use an adjusting screw d screwing into its spring pocket l , which screw may be adjusted directly or through suitable intermediate provisions to lift the yoke from the top casing. As shown, the casing is provided with a projection t , which is cylindrical and has a concave end. The projection t is similar to like projections t^1 and t^2 on the lower casing corresponding to the bearings D^1 and D^2 , which projections on the casing are used as spring holding provisions for maintaining the spring in proper relation to the yoke in each instance. These are preferably long enough to support the outer end of the yoke through

the medium of the spring, in case this is desired. The washer v is identical with similar washers which are used between the adjusting screw and spring for each of the lower yokes.

Another feature of improvement consists in utilizing the weight in the upper yoke as an auxiliary means of generating crushing pressure. This I preferably accomplish by utilizing the angularity of the supports for the bearings, so that the weight carried by them tends to force the lower rolls outwardly against the inner face of the ring, and preferably by using part of the weight of the upper roll to press outwardly the lower bearings.

In machines of this character the crushing pressure has been carried on the bearings. When the machine is empty, the rolls run directly against the face of the ring, but when material is fed on to the inner face the rolls are more or less separated from this face by the thickness of the layer of material being crushed which rests on the face. The greater this thickness the greater the crushing pressure to be resisted by the bearings. My invention provides means for relieving the bearings of part of this work, and means for transmitting the resistance of the work being done by one roll to the other rolls as a crushing force. I prefer to do this by interposing between the rolls or a part carrying them, an intermediate roll p^4 against which the crushing rolls may run intermittently or continuously. While the intermediate roll p^4 may be utilized as a driver for all the other rolls, I prefer to make it a mere idler or disk as shown, carrying it on grooved hubs or spindles q^4 on the other rolls, so that it is normally in contact with the lower hubs or in such position that it will be engaged by these in case either moves inward a predetermined distance. In such case the intermediate roll will be poised between the three rolls so as to distribute to each an equal pressure, and will run as an idler or antifriction roll between them, transmitting the thrust of each to the others, and correspondingly relieving the bearings of each. The intermediate roll is carried in grooves in the hubs or otherwise freely mounted so that it can adapt itself to variations in the relative positions of the crushing rolls, and thus compensate for the lack of uniformity in their relative movement. It may be a single solid roll of suitable peripheral contour to properly coact with the portion of the other rolls, or their shafts, with which it contacts. I prefer to form it as a free outside roll in two halves or disks one at each side of the machine. This intermediate roll makes it possible to so construct the machine that all the crushing strains are consumed within the ring and rolls, so that the bearings may serve as mere guides for

the crushing rolls. It greatly reduces friction and outside strains, and where desired, enables the elimination of independent crushing pressure such as that generated by 5 springs and weights. For some uses this will be a convenient provision, as it enables the absolute limitation of movement of the crushing rolls inwardly in cases where inward movement would be objectionable.

10 This part of my invention provides for mechanically transmitting the inward thrust of each roll to one or all the other rolls, or for definitely locating the rolls and ring as to clearance for the passage of material being crushed.

In crushers of this type the ring is generally provided with a concave crushing face, and the rolls with convex faces.

15 In operation, the ring and rolls will be driven to make the side of the ring near the feed end of the casing move in a downward direction, and at sufficient speed to cause the material to be crushed to be held on the inner face of the ring by centrifugal force. 20 The feed will enter through the chutes, fall on to the inner face of the ring, and be crushed as it passes the rolls. The speed of feed will be adjusted to approximately maintain a predetermined depth of material 25 on the inner face of the ring. If the machine is to run while using the intermediate roll p^4 , the latter will be adjusted and the weight of the crushing parts alone, or the tension of the springs, or both combined, 30 will be used to produce the crushing power.

35 In operation, when the top roll is mounted free to move, it will be adjusted vertically to the desired position. The other rolls will be pressed against the ring by their weight acting through their swinging supporting links $G G^1$, or by the weight of the top roll acting through the rolls or disks p^4 , or by both, or by their pressure springs, as desired. The 40 direction of drive of the top shaft will be such that the top of the ring will move toward the feed roller C^1 . Feed will be delivered by the feeders through both feed spouts, and will be discharged on the inner face of the ring in front of the feed roll. 45

50 The material fed will travel around with the ring and be crushed as it passes the rolls. The latter will move inwardly and outwardly within any limitations permitted by disks p^4 according to the depth of material 55 on the inner face of the ring, and will follow the movements of the ring. The speed of feed will be suitably adjusted. In case of an unusually heavy feed, the rolls will move toward each other until the thrust

60 rolls or disks p^4 are in contact with the hubs of the crushing rolls, whereupon the thrust roll will revolve with them and transmit much of the thrust from each to the others, correspondingly relieving the shaft bearings of pressure. As the ring lowers with

wear of the top roll, the top yoke will be moved by its adjusting screw. The top roll or the thrust rolls will be adjusted inwardly to make up for wear on the other rolls. The thrust rolls will bear on the side hubs q^4 or 70 the shafts of the other rolls, instead of on their centers, as these are less liable to wear than is the middle part of each roll.

75 It will be seen that my invention provides improvements which can be variously and advantageously availed of, and it will be understood that the invention is not limited to the particular combination of features and details of construction or arrangement herein described as constituting its 80 preferred form, but that it can be employed in whole or in part according to such modifications as circumstances or the judgment of those skilled in the art may dictate, without departing from the spirit of the in- 85

In the form illustrated the thrust roll is an outside disk p^4 concentric of the ring and engaging projecting hubs or spindles q^4 on three crushing rolls eccentric thereof, but 90 any number of crushing rolls may be used.

95 As shown, the outer end of each lower yoke is additionally guided by a link H , which is fulcrumed to the lower casing at I and to the yoke at J , so that it movably supports this end of the yoke from the casing and tends to move the end of the yoke outwardly as the outer end of the link is depressed. To carry the link H , the yoke is formed with ears w to which the link is 100 pivoted, and the base is formed with ears x to which the link is pivoted.

What I claim is:—

1. In combination, an annular crushing die revolving in an approximately vertical plane and having an internal crushing face, two rotatable crushing rolls movable toward and from each other within and eccentric of said die, each having a peripheral crushing face reciprocal to the inner face of 105 said die, means for revolving one of said parts, a casing affording a crushing chamber and having a wall at the side of said parts, axles or studs on which said rolls are mounted respectively, non-rotary means 110 carrying said axles or said studs respectively, and expansively acting means disposed exteriorly of said wall and intermediate of said axles or studs pressing said rolls outwardly away from one another to generate a crushing pressure toward the inner 115 face of said die.

120 2. In combination, an annular crushing die revolving in an approximately vertical plane and having an internal crushing face, 125 two rotatable crushing rolls movable toward and from each other within and eccentric of said die, each having a peripheral crushing face reciprocal to the inner face of said die, means for revolving one of said parts, a 130

1 casing affording a crushing chamber for said parts and comprising a wall at the side thereof, axles or studs on which said rolls are mounted respectively, non-rotary members carrying said axles or studs respectively, expansively acting means disposed at the side of said rolls outwardly of said wall intermediate of said non-rotary means and pressing said axles or studs outwardly away from one another to press said rolls outwardly to generate a crushing pressure toward the inner face of said die, and a third roll within said die.

3. In combination, an annular crushing die revolving in an approximately vertical plane and having an internal crushing face, two rotatable crushing rolls within and eccentric of said die, and each having a peripheral crushing face reciprocal to the inner face of said die, means for revolving one of said parts, axles or studs movable toward and from each other on which said rolls are mounted respectively, non-rotary means on which said axles or studs are mounted respectively, and expansively acting means at the side of said rolls and intermediate of said axles or studs pressing the latter outwardly away from one another to generate a crushing pressure toward the inner face of said die.

4. In combination, an annular crushing die revolving in an approximately vertical plane and having an internal crushing face, two rotatable crushing rolls movable toward and from each other within and eccentric of said die and each having a peripheral crushing face reciprocal to the inner face of said die, means for revolving one of said parts, axles or studs on which said rolls are mounted respectively, movable downwardly and outwardly away from each other, non-rotary means carrying said axles or studs, and expansively acting means disposed at the side of said rolls and intermediate of said non-rotary means and acting to press said rolls downwardly and outwardly away from one another to generate a crushing pressure toward the inner face of said die.

5. In combination, an annular crushing die revolving in an approximately vertical plane and having an internal crushing face, three rotatable crushing rolls within and eccentric of said die and each having a peripheral crushing face reciprocal to the inner face of said die, one of said rolls mounted near the upper part of said die and the others of said rolls movable toward and from each other and mounted near the lower part thereof, means for revolving one of said parts, a casing affording a crushing chamber for said parts and comprising a wall at the side thereof, axles or studs on which said rolls are mounted respectively, non-rotary means carrying said upper roll, movable non-rotary means carrying said

lower rolls respectively, and pressing means disposed at the side of said rolls exteriorly of said wall intermediate of said non-rotary means acting downwardly and outwardly to press said lower rolls outwardly away from one another to generate a crushing pressure toward the inner face of said die and reacting upwardly toward said upper non-rotary means to resist such pressure.

6. The combination with an annular die, an upper roll therein, and two lower rolls therein, and means for driving one of said parts relatively to the others, of a movably mounted roll at the side of said lower rolls for transmitting the thrusts of each to the spindle of the other.

7. The combination with an annular die and a plurality of crushing rolls therein, of a yielding roll between said rolls for transmitting the thrust from one to the spindle of the other.

8. In combination, an annular crushing die having an internal crushing face, a rotatable crushing roll within and eccentric of said die and having a peripheral crushing face reciprocal to the crushing face thereof, means for revolving one of said parts, means on which said roll is rotatably mounted, and a roll at the side of said roll mounted to revolve on an axis radially inwardly thereof and engaging said roll inwardly of its crushing face for sustaining it against a pressure from the inner face of said die.

9. In combination, an annular crushing die having an internal crushing face, a rotatable crushing roll within and eccentric of said die and having a reduced hub or spindle at each side of said die, means for revolving one of said parts, and a roll at each side of said crushing roll revolving on an axis radially inwardly thereof and engaging said reduced portion or spindle to resist an inward pressure from the inner face of said die.

10. In combination, an annular crushing die revolving in an approximately vertical plane and having an internal crushing face, a rotatable crushing roll within, eccentric of and disposed near the upper part of said die and having a reduced portion or spindle at the side thereof, and having a peripheral crushing face reciprocal to the crushing face of said die, means for revolving one of said parts, and a roll or rolls at the side of said crushing roll engaging the reduced portion or spindle thereof to resist a crushing pressure from the inner face of said die.

11. In combination, a crushing die revolving in an approximately vertical plane and having an internal crushing face, two rotatable crushing rolls within and eccentric of said die and each having a peripheral crushing face reciprocal to the crushing face

of the latter, and a reduced portion or spindle at the side of said die, and a roll intermediate of and engaging the reduced portions or spindles of said rolls to sustain them against a crushing pressure from the inner face of said die.

12. In combination, an annular crushing die having an internal crushing face, three rotatable crushing rolls within and eccentric of said die, each having a peripheral crushing face reciprocal to the crushing face of the latter and each having a portion or spindle at its side, and a roll at the side of said rolls intermediate of and engaging said portions or spindles to transmit the stress of each to the others.

13. In combination, a revolving crushing die having an internal crushing face, three rotatable crushing rolls within and eccentric of said die, each having a peripheral crushing face reciprocal to the crushing face of the latter, means for revolving one of said parts, non-rotative means on which said rolls are rotatably mounted, and a roll intermediate of said means engaging said crushing rolls outwardly of their crushing faces for resisting a crushing pressure from the inner face of said die.

14. In combination, a crushing die revolving in an approximately vertical plane and having an internal crushing face, two movable and rotatable crushing rolls within and eccentric of said die and each having a peripheral crushing face reciprocal to the inner face of the latter, means for revolving

one of said parts, non-rotative means movable toward and from each other on which said rolls are rotatably mounted respectively, and means at each side of said rolls outwardly of their crushing faces acting to press said rolls outwardly away from one another to generate a crushing pressure toward the inner face of said die.

15. In combination, a crushing die revolving in an approximately vertical plane and having an internal crushing face, three rotatable crushing rolls within and eccentric of said die, each having a peripheral crushing face reciprocal to the crushing face of the latter, one of said rolls disposed near the upper part of said die and two of said rolls disposed in the same plane below said upper roll, means for revolving one of said parts, non-rotary means movable toward and from each other on which said rolls are rotatably mounted respectively, and a roll at the side of said rolls and intermediate of their axles receiving the downward stress of said upper roll and dividing it between said lower rolls to hold them outwardly to resist a crushing pressure from the inner face of said die.

In witness whereof, I have hereunto signed my name in the presence of two subscribing witnesses.

GEORGE H. FRASER.
